CLAIM

The ornamental design for a gas fryer cooking chamber, as shown and described.

DESCRIPTION

FIG. 1 is a front (isometric) perspective view of a gas fryer cooking chamber according to the present invention, showing the environment (the remainder of the gas fryer) in dash lines.

FIG. 2 is a front top perspective view of the cooking chamber of FIG. 1 shown removed from the gas fryer environment.

FIG. 3 is a rear top perspective view of the cooking chamber of FIG. 2.

FIG. 4 is a top view of the cooking chamber of FIG. 2. FIG. 5 is a front view of the cooking chamber of FIG. 2. FIG. 6 is a rear view of the cooking chamber of FIG. 2. FIG. 7 is a left side view of the cooking chamber of FIG. 2, the right side being a mirror image thereof.

FIG. 8 is a cross-sectional view of the cooking chamber of FIG. 2, taken along line 8-8 of FIG. 4; and,

FIG. 9 is a cross-sectional view of the cooking chamber of FIG. 2, taken along line 9-9 of FIG. 4.

Any elements shown in broken lines form no part of the claimed invention. The broken lines are shown for environmental purpose only and form no part of the claimed design. The dash-dot broken lines adjacent to the shaded or sectional portions form an unclaimed boundary of the design.
